UNITED STATES PATENT OFFICE.

JOSEPH A. IMHOFF, OF NEW YORK, N. Y., ASSIGNOR TO KAUFMANN & STRAUSS CO.,
OF NEW YORK, N. Y., A CORPORATION OF NEW YORK.

DISPLAY-STAND.

1,094,995.

Specification of Letters Patent. Patented Apr. 28, 1914.

Application filed November 17, 1913. Serial No. 801,511.

To all whom it may concern:

Be it known that I, JOSEPH A. IMHOFF, a citizen of the United States, residing at New York, in the county of New York and State of New York, have invented certain new and useful Improvements in Display-Stands; and I do hereby declare the following to be a full, clear, and exact description of the invention, such as will enable others skilled in the art to which it appertains to make and use the same.

This invention relates to display stands and has for an object to provide a novel means for supporting a carton or the like.

15 A further object of this invention is to provide an improved means for positioning a carton or the like upon a display stand and to lock said carton to said display stand when the same has been properly set up.

20 Further objects will be apparent from the following specification, appended claims and drawings in which,

Figure 1 is a perspective view of the display stand set up and with the carton placed thereon. Fig. 2 is a perspective view of the display stand with the carton removed. Fig. 3 is a rear view of the blank from which the display stand is formed, and, Fig. 4 is a cross sectional view showing how the carton 30 is locked to the display stand.

In carrying out this invention, the display stand presents an extended hand having the palm thereof disposed to serve as a support for a carton. When the carton has been placed upon the hand properly it is locked thereto so that the same may not be displaced accidentally.

In carrying out this invention, there is shown a blank 10 which represents an extended hand having certain fingers thereof extended upwardly to form projections 11 and 12. The blank is scored as at 13 to enable a bed portion 14 being folded from a plane common to the portion 10 and, to permit the projections 11 and 12 to remain in the same plane as the portion 10, the bed portion 14 is cut about the outline of the projections 11 and 12 where necessary. The scoring 13 may be run across the blank at 50 any desired portion to give the proper pitch to the bed portion 14 when the display stand is set up. The bed portion 14 has an extension 15 therefrom which is cut as at 16 to enable the extension 15 being bent out of

the plane of the bed portion 14 and, this 55 extension is separated by the cut 16 to form an over-hang as will be hereinafter described. The blank is maintained in the desired upright position by an easel 17 which may have a leaf portion 18 glued or 60 otherwise secured to the back 10. This easel portion has the upper edge thereof inclined to the desired pitch and has an over-hanging projection 19 formed at the uppermost end thereof. The extension 15 may have line of 65 scoring 20 formed across the base thereof to enable said extension being more easily bent.

When a box is placed upon the stand for display purposes after the bed 14 has been folded on the line of scoring 13 and after the 70 easel 17 has been swung to cause the over-hanging projection 19 to engage the edge of the bed 14, the carton may be placed upon this bed to have one corner thereof pass between the projections 11 and 12 as shown in 75 the drawing after which, the projection 15 may be raised from the plane of the bed 14 to engage the flange formed about the lower edge of the carton and the overhanging projection may likewise be 80 swung to engage the flange about the bottom of the box on the opposite side thereof. It is apparent that the binding action between the projections 15 and 19 form a lock which securely holds the carton against 85 accidental displacement.

Modifications may be made within the scope of this invention without departing from the spirit thereof and the drawing submitted is for illustrative purposes only. 90

Having thus described my invention, I claim,

1. In a display stand, a blank having portions foldable therefrom to form a bed plate, portions struck from said foldable portions 95 to form projections in the plane of said blank, an overhanging projection carried by said bed portion, the easel carried by said blank, an overhanging projection carried by said easel, and said overhanging projections 100 carried by said bed portion and said easel forming locking means for a carton placed upon said bed portion.

2. In a display stand, a blank, a portion thereof foldable along a demarcation to 105 form a bed portion, projections struck from said bed portion to remain in the plane of said blank and to rise above said bed por-

tion, a projection struck from said bed portion to be bent above the plane of said bed portion and to have an overhanging edge, from the plane of said bed portion, a projection to overhang the rear edge of said bed portion, and said projection struck from said bed portion together with the projection from said easel forming a locking

means for a carton placed on said bed portion.

In testimony whereof I affix my signature in presence of two witnesses.

JOSEPH A. IMHOFF.
